UNITED STATES PATENT OFFICE.

EDWARD ALBERT ROCKWELL, OF NEW YORK, N. Y.

CARBURETER.

1,360,025.

Specification of Letters Patent. Patented Nov. 23, 1920.

Application filed July 28, 1916. Serial No. 111,755.

To all whom it may concern:

Be it known that I, EDWARD A. ROCKWELL, a citizen of the United States, and a resident of the city, county, and State of New York, have invented certain new and useful Improvements in Carbureters; and I do hereby declare the following to be a full, clear, and exact description of the invention, such as will enable others skilled in the art to which it appertains to make and use the same.

This invention relates to carbureters for internal combustion engines and has for its object to provide a novel carbureter in which the proportion of fuel and air in the combustible mixture will be automatically varied for different engine speeds to obtain the proper mixture for best operation at the particular speed and load.

A further object of the invention is to provide a fuel feed for the novel carbureter by means of which the feed of fuel to the spray nozzle will be maintained constant under a constant head without being affected by the relative elevation of the supply tank and the carbureter. By my improved feed the gasoline will be drawn from the supply tank at the proper rate to maintain the constant head, with the supply tank below the level of the novel carbureter and at atmospheric pressure.

In present automobile practice the supply tank is either so positioned on the car as to always be above the level of the carbureter, or else auxiliary devices are used for forcing or drawing the fuel from the main supply tank to a local feed tank adjacent the motor. The first described method can be employed only in bodies of certain types, and in any case is unsatisfactory for the reason that the level on which the car is resting varies the head of the feed. The auxiliary devices, while obviating the defects of the gravity system to a large extent add complication and cost to the structure. With my improved feed no auxiliary apparatus is required, the suction feed being incorporated in and forming an indivisible part of the carbureter itself.

A further object of the invention is to provide a carbureter having the above features, in which the structure contains a minimum of working parts and is free from complication and necessity of fine adjustment.

In the preferred embodiments of the in-

vention disclosed herein the level of the fuel in the feed chamber may be varied by the adjustment of a single threaded part and the regulation of the carbureter both for fixed adjustment and for running control of the motor is effected through the adjustment of a single part.

Further objects of my invention will appear from the following specification, taken in connection with the accompanying drawings, wherein—

Figure 1 shows one embodiment of my improved carbureter in vertical section; Fig. 2 is a vertical sectional view on line 2—2 of Fig. 1;

Figs. 3 and 4 are detail views of different portions of the carbureter; and

Fig. 5 is a vertical sectional view of a portion of the carbureter showing a modified form of fuel feed.

Referring now to the drawings, 1 indicates the main casting embodying, as shown, a mixing tube or chamber 2 water-jacketed as indicated at 3, for connection with the water circulating system of the motor to raise the temperature in the mixing chamber and assist in the vaporization of the fuel.

The main casting is designed at its upper end to connect directly with the intake manifold 4 of the motor, and form a downward vertical extension of the manifold intake, and is provided at its lower end with a lateral, horizontal extension having near its end an opening for the admission of the air through the air-controlling valve 5 whose specific construction will be later described.

The liquid fuel is, in the embodiment shown in Figs. 1 to 4, supplied to the mixing tube through a spray nozzle 6, projecting upwardly from the lower wall of the horizontal extension of the mixing tube. As shown, the spray nozzle comprises a tube threaded in the wall of the casting with its upper end ground to provide a seat for the valve 7 by means of which the quantity of fuel will be regulated at the spray nozzle.

In the construction shown, the fuel is delivered to the spray nozzle by a supply pipe 12 preferably connected to the spray nozzle through passage 9 in the casting into which the lower end of the spray nozzle projects; the end of the spray nozzle preferably extending into a cavity formed in, *e. g.*, the upper face of a plug 10, which may be

threaded in the bottom wall of the casting to provide a settling chamber for small particles of grit which might otherwise clog the spray nozzle.

5 The supply pipe 12 is not, in this embodiment, connected directly to the supply tank, but, as shown more particularly in Fig. 1, preferably connects with a chamber 14 herein termed the "constant-level" chamber, 10 which may be formed in a lateral projection of the main casting near its upper end, preferably several inches above the outlet of the spray nozzle. Also formed in the casting below the chamber 14 and separated from 15 it by, for example, a web 15 is shown a second chamber 16, herein termed, for convenience, the "filtration" chamber, to which may be connected the supply pipe 17 from the fuel tank. The web 15 is shown 20 provided with a central tubular extension affording a valve-controlled passage between the chamber 16 and the upper "constant-level" chamber 14, and surrounding the extension is shown a strainer or filter 25 18 of gauze, or the like, which may be clamped in place by means of a plug 19 which may close the bottom of the filtration chamber 16, the construction being such that the strainer may be conveniently re- 30 moved and cleaned or renewed.

The valve between the two chambers may consist of a ball 20 lying in the bore of the projection and resting against a valve seat surrounding the upper face of the passage 35 through the web. The ball may be held against the seat by, *e. g.*, a spring 21, whose upper end may project into a counterbored cavity in the lower end of a nozzle 22 which may be threaded into the web 15, as shown, 40 to provide an inlet for the fuel at the upper end of the nozzle through, *e. g.*, the lateral bores 23.

Surrounding the upper end of the nozzle 22 is shown a hollow plug 24 threaded into 45 the upper wall of the "constant-level" chamber 14, the walls of the plug being inwardly tapered at its lower end to provide a somewhat separate portion or compartment of said chamber surrounding the inlet 50 23 and also to provide a lower opening of a bore ordinarily about equal to the external diameter of the nozzle. The upper end of the hollow plug 24, which may be vertically adjusted by rotation, in order to vary 55 the "head" at the nozzle 6, is shown as closed by a plug 26, having a vent opening 27 of very small diameter, and above the plug 26 a perforated cap 28 and gauze diaphragm 28^a may be provided to protect the 60 vent opening from clogging.

The outer surface of the nozzle 22 may be fluted as shown at 29 in enlarged detail in Fig. 4, for a distance somewhat above and below the lower end of the hollow plug 24

to provide a passage for the fuel from the 65 hollow plug to the chamber 14, and thence through the pipe 12 to the spray nozzle.

The length of the fluted portion is shown as extended beyond the necessary distance 70 for the passage of the fuel in order to permit a vertical adjustment of the hollow plug to vary the level of the fuel in the chamber 14, as will be later described.

The "constant-level" chamber 14 is shown connected with the mixing tube 2 by an upwardly inclined orifice 30 above the end of the hollow plug 24, so that the pressure on the liquid in the chamber 14 is reduced upon each suction stroke of the piston of the engine, maintaining in effect a substantially 80 constant sub-normal pressure in the "constant-level" chamber 14. The tension of the spring of the ball valve is intended to be so adjusted that it will maintain the passage from the supply chamber 16 to the chamber 85 14 closed against the gravity pressure of the fuel in case the supply tank is at a higher elevation than the filtration chamber 16. A very light pressure will suffice for this purpose, so that the suction in the fuel chamber 90 will be ample to lift the valve and feed the fuel. The vent 27 is provided in order that the pressure in the chamber within the hollow plug 24 shall become atmospheric whenever the portion of the chamber within 95 the plug is cut off from the remainder of the "constant-level" chamber 14.

Assuming the level of the liquid to be as shown in the drawing the constant head in the chamber 14 will supply fuel to the spray 100 nozzle 6, where it will be atomized and drawn into the engine. When the fuel level in the chamber 14 falls below the opening into the hollow plug 24, the pressure within the chamber of the hollow plug will be reduced, the cross-section of the vent 27 being too small in comparison with the total area of the fuel passage formed by the fluted surface of the nozzle to materially affect the reduction in pressure. The suction will 110 thereby be effective at the feed openings 23 of the nozzle 22 to open the ball valve and draw fuel from the chamber 16 into that portion of the "constant-level" chamber that is within the plug, whence it passes into 115 the other part of chamber 14, raising the level of the fuel.

The ball valve will maintain the filtration chamber 16 full of fuel when the tank is lower than the chamber, for any flow toward the tank will immediately cause the valve to close even before the vent 27 has re-established the air pressure in the hollow plug to atmospheric. To prevent an excessive pressure reduction in the chamber 14 a spring 120 loaded safety valve may be provided as conventionally indicated at 39. This valve, involving no features of novelty, may contain

a ball and a spring similar to the ball 20 and spring 21.

The bore of the nozzle 22 and its outlet ports are sufficiently large to supply the fuel 5 when the ball valve is opened by the suction of the engine at a much more rapid rate than the consumption of the fuel by the engine, so that the level of the fuel in the "constant-level" chamber 14 will quickly rise, to 10 cover the opening from the plug into the lower part of the "constant-level" chamber 14. The interior of the hollow plug will then be no longer equally affected by the suction of the engine, the flow of fuel thereto 15 will be checked and through the vent 27 the pressure on that portion of the chamber that is within the plug will again become atmospheric.

The effect of this operation is to maintain 20 a level of the fuel in the "constant-level" chamber 14 at substantially the lower edge of the hollow plug and thereby maintain the spray nozzle under a fixed head or feed pressure, regardless of the level of the supply 25 tank, and whether the car is running up hill or down hill.

In Fig. 5, omitting disclosure of any filtration means, I have shown a modified form of suction feed wherein the level of the fuel 30 is maintained by means of a float feed valve. As here shown the "constant-level" or float chamber 50 is formed in a projection on the mixing tube located in a position corresponding to the fuel chamber of the preferred design. The exit pipe 12 leads from 35 the float chamber near the bottom thereof to the mixing tube, which may be of the same design as in the preferred construction and is therefore not shown in the drawings. 40 In the form shown, the inlet pipe 17 which must lead directly or indirectly from the fuel tank communicates with the float chamber through a central tube 51, which may be threaded in the cap of the float chamber, 45 the threads of the lower end of the tube being preferably machined off to serve as a guide for the float 52 here shown as of the usual hollow metal construction. The lower end of the tube 51 is ground to form 50 a valve seat for co-operation with the float valve 53 carried by a bridge-piece 54 attached to the bottom of the float. When the level of the fuel in the float chamber rises above the desired point, the buoyancy 55 of the float will raise the valve against the valve seat and cut off the fuel. The level may be varied by adjusting the tube 51 up and down in its threaded bearing in the cap on the float chamber.

60 The cap of the float chamber is shown provided with a suitable air-tight closure, and the space above the level of the fuel in the chamber is shown connected with the mixing tube by a port 55, so that the suc-

tion of the engine will maintain a sub- 65 atmospheric pressure in the float chamber to positively draw the fuel in the float chamber from the supply tank, even though the level of the tank be below that of the float chamber. As the bore of the feed tube 51 70 may be very small while the float may be made of any desired diameter, the reduced pressure of the float chamber will not be sufficient to open the valve against the buoyancy of the float, but when the valve is 75 opened by the descent of the float with the lowering of the liquid level, the suction produced in the float chamber by its connection with the intake of the engine will positively feed the fuel into the float chamber. 80

The mechanism for simultaneously regulating the fuel and air will now be described. The lateral extension of the main casting is shown as fully open at its outer end, and telescopically mounted in the bore 85 of the projection is a valve sleeve 31 having at its inner end a cam 32 extending through about half the circumference of the sleeve and operatively engaging the needle valve 7 of the spray nozzle. The needle valve is 90 shown as held in normally elevated position by a suitable spring and is intended to be more or less closed by the rotation of the cam according to the rotative adjustment of the sleeve 31. 95

In the form shown the air is admitted to the mixing tube through a lateral opening 34 in the tube wall and thence to the bore of the valve sleeve through an opening 35 in the wall of the valve sleeve. The opening 35 100 is positioned in the sleeve in such relation to the cam 32 and the opening 34 that it is adjusted across the opening 34 during the partial rotation of the valve sleeve which is effective in regulating the needle valve 105 7. The opening 34 is substantially rectangular, whereas, the opening 35 has one straight wall and one inclined wall so positioned that the rotative adjustment of the valve sleeve brings a greater or less portion 110 of the opening 35 into registration with the opening 34 to thereby vary the air supply. The valve sleeve may be rotated by means of any suitable mechanism, and I have shown for the purpose a lever arm 38 fast 115 on the end closure of the valve sleeve, suitable stops being provided to limit the extent of adjustment.

The valve sleeve is also mounted for longitudinal adjustment in the mixing tube extension, which adjustment may be effected through a cam lever 36 mounted on the main casting and engaging the projecting flange at the end of the sleeve valve, as more particularly shown in Fig. 3, and this endwise 120 movement of the valve sleeve is also effective to regulate the air supply. As one means, to this end, the straight wall of the

opening 35 is shown positioned beyond the corresponding edge of the opening 34, so that outward movement of the valve sleeve will bring the opposite wall of the opening 35 toward the edge of the opening 34 and thereby cut down the area of the opening. The cam 32 is of sufficient width to permit the endwise adjustment of the sleeve without disengaging the head of the needle valve.

By rotatively adjusting the valve sleeve the quantity of fuel delivered from the spray nozzle will be varied with the variations in area of the air opening. When, however, the valve is longitudinally adjusted, by means of the cam lever 36, the air opening only will be adjusted.

The operation of the device is as follows: Let it be assumed that the carbureter is attached to an automobile proceeding on a level road under conditions to place a light load on the motor. A reasonable speed of the car will therefore be maintained with small fuel consumption, and it will be assumed that the engine is receiving a proper mixture with the feed valve adjusted to the position shown in the drawings. Let it be supposed that the car has reached a hill, which causes the motor to slow down. To increase the power of the motor so that it may drive the car up the hill, the sleeve valve is rotated by means of the lever arm 38 through connection to the usual steering post control of the automobile, in a direction to the right, or clockwise, as shown in Fig. 2, to thereby increase the opening of the needle valve and simultaneously increase the area of the air inlet. The suction of the motor will now be effective to draw in an increased amount of air on each stroke through the increased air opening, and through the adjustment of the needle valve a greater quantity of the fuel will be discharged so that the engine will receive a more powerful charge at each stroke, and deliver greater power at the shaft.

By giving the proper relative contour to the inclined edge of the air opening and the operating face of the needle valve cam, any desired relation of the air and fuel feed may be maintained. In case, however, the mixture, correct for certain conditions, is found to be too rich or too lean under other existing conditions, the ratio of the air and fuel opening may be altered by adjusting the air valve longitudinally of the tube by means of the cam lever 36 to obtain the desired regulation. This lever may be connected to a suitable control on the dash of the automobile but not on the steering post for the running control, as an occasional adjustment for abnormal conditions is all that is required.

With an ordinary butterfly throttle in the mixing tube above the fuel inlet, as is com-

mon practice in carbureter construction, the amount of fuel discharged at the spray nozzle is affected by the velocity of the air in the spray tube as well as the suction, no positive means for regulating the fuel flow being provided. These factors do not maintain a uniform mixture at different motor speeds, but an auxiliary air valve has heretofore been necessary to supply an extra quantity of air to the tube beyond the fuel inlet to dilute the mixture which is too rich at high motor speeds, while at low motor speeds where the greater power is required, the mixture is liable to be too lean.

In my improved carbureter, the fuel feed is not dependent on such variable factors, but is positively controlled by the needle valve, the cam being shaped to give a sufficiently rich mixture at low speeds and a sufficiently lean mixture at high speeds to require no dilution.

My vacuum fuel feed may obviously be used without my improved control valve construction and vice versa, but I prefer to use both devices on the same carbureter for the reason that their combined use provides a proper proportion and sufficient quantity of fuel and air in the mixture in relation to the engine speed under all running conditions.

I claim:

1. In a carbureter a "constant-level" fuel chamber, a source of supply therefor, a fuel passage therefrom, means independent of said fuel passage, for producing a sub-atmospheric pressure in said chamber to positively draw the fuel into said chamber from the source of supply, and means for maintaining a fixed level of fuel in said chamber independent of the rapidity of consumption of the fuel by the motor.

2. In a carbureter, a "constant-level" fuel chamber, a source of supply therefor, a fuel passage therefrom, an inlet from the source of supply terminating in a portion of said chamber, means, independent of said fuel passage, for producing a sub-atmospheric pressure in the portion of the chamber surrounding said fuel inlet when the level of the fuel falls below a predetermined point, to thereby positively draw the fuel into said chamber from said source of supply.

3. In a carbureter, a "constant-level" fuel chamber, a source of supply therefor, a fuel passage therefrom, means, independent of said fuel passage, for producing a sub-atmospheric pressure in said chamber to positively draw the fuel into said chamber from the source of supply, and means for effecting a change toward atmospheric pressure in a portion of said chamber even after the fuel level rises above a predetermined point.

4. In a carbureter, a "constant-level" fuel chamber divided into two portions, a fuel inlet from the source of supply to one portion, said other portion having a delivery outlet to the carbureter, means for inducing sub-atmospheric pressure in the second mentioned portion of the chamber, and a passage between the two portions of said chamber so controlled by the level of the fuel as to produce a sub-atmospheric pressure in the first mentioned chamber when the level of the fuel falls below the said passage.
5. In a carbureter, the combination of a mixing tube to be connected to an intake on the motor, a fuel chamber adjacent said mixing tube, a port connecting said chamber to said mixing tube whereby the suction on the motor produces a sub-atmospheric pressure on the fuel in the fuel chamber to positively draw the fuel into the fuel chamber, and means, controlled by the level of the fuel in the chamber, for checking the flow of fuel to the chamber when the level rises above a predetermined point.
6. In a carbureter, the combination of a mixing tube to be connected to an intake on the motor, a fuel chamber adjacent said mixing tube, a port connecting said chamber to said mixing tube whereby the suction on the motor produces a sub-atmospheric pressure on the fuel in the fuel chamber to positively draw the additional fuel into the said chamber, means, controlled by the level of the fuel in the chamber, for checking the flow of fuel to the chamber when the level rises above a predetermined point, a spray nozzle terminating in the mixing tube at a point below the fuel chamber, and means for varying the predetermined level of the fuel in the fuel chamber to thereby vary the pressure head on the spray nozzle.
7. In a carbureter, the combination of a mixing tube, a "constant-level" fuel chamber adjacent said mixing tube, a port between the upper portion of a lower compartment of said "constant-level" fuel chamber and the mixing tube, whereby the suction of the engine produces sub-atmospheric pressure in the said lower compartment, a second or upper compartment of said fuel chamber, a passage between the said second compartment and the said lower compartment, said passage being at a level below that of the said port into the mixing tube, and a feed passage from the source of supply terminating in said upper compartment, whereby the said sub-atmospheric pressure in the lower portion of said "constant-level" chamber is effective to draw fuel through the mentioned passage whenever the level of the fuel falls below the level of the passage between the upper and lower compartments of the "constant-level" and the chamber.
8. In a carbureter, the combination of a mixing tube, a fuel chamber adjacent said mixing tube, a port between the upper portion of a lower compartment of the fuel chamber and the mixing tube whereby the suction of the engine produces sub-atmospheric pressure in the said compartment, a second compartment in said fuel chamber, a passage between the second compartment and the lower compartment of the said chamber, said passage being below the port into the mixing tube, a feed passage from the source of supply terminating in said second compartment, and an air opening into said second compartment whereby the compartment is normally maintained at atmospheric pressure except when the level of the fuel in the lower compartments of the chamber falls below that of the passage between the respective compartments.

In testimony whereof I affix my signature. 85
EDWARD ALBERT ROCKWELL.
